UNITED STATES PATENT OFFICE

RICHARD GRIFFITH, OF HYDEVILLE, VERMONT, ASSIGNOR, BY MESNE ASSIGNMENTS, TO THE GARDNER-DENVER COMPANY, OF QUINCY, ILLINOIS, A CORPORATION OF DELAWARE

GUIDE FOR ROCK DRILLS

Application filed November 5, 1926. Serial No. 146,519.

The present invention relates to means for positioning a drill steel, and the object is to provide a novel structure, by means of which a series of holes can be drilled at absolutely 5 equi-distant points, and with great accuracy, thus obviating serious difficulty heretofore experienced in connection with the drilling of holes where they are apt to run off at various angles, and thus leave different thicknesses of material between them.

In the accompanying drawings:

Figure 1 is a side elevation of one embodiment of the invention,

Figure 2 is a plan view of the same,

15 Figure 3 is a vertical sectional view on the line 3—3 of Figure 1,

Figure 4 is an end elevation,

Figure 5 is a plan view of the bushing employed.

20 In the embodiment disclosed, an elongated body, preferably of one piece, is provided. In the present structure, this body is shown as comprising an upper horizontal bar 4 and a lower horizontal bar 5 connected by integral end portions 6, though other forms may be employed. Through the bars 4 and 5 are formed vertical guide openings 7, these openings being of sufficient diameter to permit the passage therethrough of the bit of a drill 25 steel, and consequently being of greater diameter than the shank of such steel. The end portions are provided with vertical bores 30 8 and 9.

35 In the bore 8 is located a vertically disposed anchor stem 10 that is slideable in said bore and extends a considerable distance below the body. This stem is of a size to engage in a hole drilled in the rock. The stem is provided with a longitudinal groove 11 40 that is preferably tapered downwardly, and in said groove is slidably fitted a clamping wedge 12 that projects above the upper end of the stem and extends below the body. This wedge has its upper end portion projecting outwardly beyond the stem, and fitting in a groove 13 formed at one side of the opening 8. The projecting portion is provided with a series of teeth 14. The end 45 of the body outside the groove 13 is enlarged 50 at 15, and is formed with a notch or seat 16.

The bottom of this seat 17 constitutes the fulcrum for a tool lever 18. The inner end of said lever is tapered to form a tooth 19 adapted to engage with the teeth 14. The stem furthermore is provided below the body with 55 a cross pin 20, the length of which is greater than the diameter of the drilled hole, and this cross pin is also adapted to seat in notches 21 formed in the bottom of the body alongside the opening 8, and said pin prevents detachment of the stem from the body 4.

In the other end bore 9 is fitted a holding stem 22 that projects above and below the body, the upper end constituting a hammering head, the lower end being sharpened to 65 form a bit 23. Set screws 24 serve to clamp the two stems against movement.

A bushing is provided to detachably fit in the guide openings 7. This bushing preferably consists of longitudinal sections 25 having flanges 26 formed on their upper ends and adapted to rest on the top of the body. The bore of the bushing is such that it will snugly but slidably receive the drill steel. A portion of such steel is shown at 27, the bit 75 thereof being indicated at 28.

This structure is used substantially as follows. When a hole has been drilled, the lower end of the stem 10 is engaged therein, the cross pin 20 limiting the downward movement of said stem into the hole. The body is then moved until the series of guide openings 7 are directly over and in line with the points for the series of holes to be drilled. The wedge 12 is then driven downwardly and serves to securely fix the stem in the drilled hole, as well as fasten the body to the stem. The supporting pin is then driven into the stone a short distance as indicated in Figure 90 1 and is clamped by the set screws. The bit of the drill steel is then passed through the first opening and the shank is afterwards surrounded by the bushing fitted into said opening. The steel is thus accurately positioned 95 and the first hole is drilled. After the completion of the hole, the steel is moved to the next hole and so on until the series is completed. The implement is then moved to the position to drill the next set of holes, the 100

anchor stem being now engaged in the hole last drilled.

It has been found under actual practice that this device will guide the drill steel with the greatest accuracy, thus insuring that the holes are drilled a predetermined distance apart and are equi-distant throughout their extent.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim, is:

1. In a rock drill guide, the combination with a body having a guideway for the drill steel, of an anchor movably mounted on the body and adapted to engage in a drilled hole, and means for limiting the amount of insertion of the anchor into the hole, said means also engaging the body and limiting the movement of the anchor in one direction therein.

2. In a rock drill guide, the combination with a body having guideways for the drill steel and also having a bore at one side of the guideways, of an anchor stem slidably mounted in the bore, and means for securing the stem against its sliding movement, said stem having a cross pin beneath the body.

3. In a rock drill guide, the combination with a body having guideways for the drill steel, and a bore, of an anchor stem slidable in the bore, and a clamping wedge engaging the stem and the body for holding the stem in adjusted position.

4. In a rock drill guide, the combination with a body having guideways for the drill steel and a bore, of an anchor stem slidable in the bore, and a clamping wedge engaging the stem and the body for holding the stem in adjusted position, said wedge having a fulcrum for a releasing tool engaged with the tooth.

5. In a rock drill guide, the combination with a body having guideways for the drill steel and a bore at one end, of an anchor stem slidable in the bore and having a stop below the body, said anchor also having a longitudinal groove, and a wedge slidable in the groove and having teeth, said body having a socket opening into the bore and provided with a fulcrum bearing for a tool engaged with said teeth.

6. In a rock drill guide, the combination with a body having guide openings of sufficient diameter to allow the passage of the enlarged bit of a drill steel, of means for anchoring the body against movement, and a

bushing that detachably fits in the guide openings and having a bore that snugly and slidably receives the shank of the drill steel above the bit and permits the free movement of the steel longitudinally and rotatably with relation to the body.

7. In a rock drill guide, the combination with a body having guide openings of sufficient diameter to permit the passage of the enlarged bit of a drill steel, of means for anchoring the body, and a bushing that detachably fits in the guide openings and having a bore that snugly and slidably receives the shank of the drill steel above the bit, said bushing comprising longitudinally extending sections having outstanding holding flanges on their upper ends.

8. In a rock drill guide, the combination with a body provided with a series of vertical guide openings and bores in the ends of the body, an anchor stem slidably mounted in one bore, means for clamping the stem, a holding pin mounted in the other bore, means for securing said pin, said guide openings being of a diameter to permit the passage of the enlarged bit of a drill steel, and a split bushing that detachably fits in the openings and has a bore to snugly and slidably receive the shank of a drill steel above the bit, and permits the free movement of the steel longitudinally and rotatably with relation to the body.

9. In a rock drill, the combination with a body having a guide for a drill steel, of an anchor movably mounted in the body for engagement in a previously drilled hole, and means for wedging the anchor in the hole, said wedging means also engaging the body and constituting a key for holding the body against rotation on the anchor.

10. In a rock drill, the combination with a body having a guide for a drill steel, of an anchor movably mounted in the body for engagement in a previously drilled hole and having a keyway, the body also having a keyway aligned with the keyway of the anchor, and a wedge slidably mounted in the keyways to hold the body against rotation on the anchor, said wedge engaging the anchor to wedge it in its hole.

11. In a rock drill, the combination with a body having a plurality of guideways for directing a drill steel in the drilling of a line of holes, of an anchor stem mounted in one end of the body for engagement in a previously drilled hole, a spur shorter than the anchor stem and movably mounted in the other end of the body, said spur having exposed means by which it may be driven into the rock at the end of the line of holes determined by the guideways, and means for detachably fixing the spur against movement in the body after it has been so driven.

In testimony whereof, I affix my signature.
RICHARD GRIFFITH.
